UNITED STATES PATENT OFFICE.

AUGUSTINE DAVIS, OF CHICAGO, ILLINOIS, AND JAMES H. BIRCH, OF ELKHART, INDIANA.

ACETYLENE-GAS GENERATOR.

SPECIFICATION forming part of Letters Patent No. 752,330, dated February 16, 1904.

Application filed April 29, 1903. Serial No. 154,756. (No model.)

To all whom it may concern:

Be it known that we, AUGUSTINE DAVIS, a resident of Chicago, Illinois, and JAMES H. BIRCH, a resident of Elkhart, Indiana, citizens 5 of the United States, have invented certain new and useful Improvements in Acetylene-Gas Generators, of which the following is a specification.

Our invention relates to generating devices 10 for the manufacture of acetylene gas, more particularly for illuminating purposes; and it consists in certain improvements upon the machine disclosed in and covered by Letters Patent to Augustine Davis, No. 719,091, granted 15 January 27, 1903.

The principal objects of the present invention are, first, a more advantageous location 20 of the drainage-chamber and of the several pipes entering the same in a position where they can readily be gotten at for purposes of cleaning and repair without the necessity of partially or wholly dismantling the machine, for which purpose said drainage-chamber is in 25 accordance with our present invention located wholly outside of the generation-chamber of the machine; secondly, to get rid of the air-space in the generation-chamber, and thus lessen the danger of accidental explosions resulting from the presence of an ignitable explosive mixture of gas and air in said generation-chamber; thirdly, to get rid of air mixtures 30 in the generation-chamber, which reduce both the quantity and quality of the illumination when the generator is recharged; fourthly, to provide a simple and effective water seal 35 against the escape of gases and odor during the recharging operation, and, finally, to provide other minor detail improvements and simplifications which will hereinafter appear 40 in the subjoined description.

In the accompanying drawings we have illustrated a desirable form of apparatus in which our invention may be embodied, and referring thereto—

45 Figure 1 is an irregular vertical section through the generation-chamber and bell on the line 1 1 of Fig. 2, and Fig. 2 is a horizontal section on the line 2 2 of Fig. 1.

Referring to the drawings, 5 designates the

stationary or outer tank or shell of the device, 50 which is preferably in the cylindrical form shown. The upper open end of the tank 5 is entered by an annular-shaped bell 6. Within said tank, at the lower end thereof, is located the generation-chamber 7, the side walls of 55 said chamber being constituted by the cylindrical walls of the outer shell or tank 5 and its upper and lower walls being constituted by conical plates or partitions 8 and 9, respectively. The generation-chamber 7 opens 60 freely into the lower end of a carbide-feed chamber 10, disposed thereabove and coaxially therewith, this chamber being preferably formed by a tube or cylinder 11, resting upon or formed integral with the upper partition 8, extending upwardly and coaxially through the bell 6 and having a sufficient diameter to admit a carbide-receptacle 12 and a carbide-feed mechanism 13 in the upper end thereof and permit the unobstructed fall of 65 the carbide therefrom into the generation-chamber. The concave bottom plate 9 has a downwardly-inclined lateral outlet-tube 14, the outer end of which is closed by a pivoted gate-valve 15.

75 16 designates as an entirety a weight-operated carbide-feed motor located above the carbide-receptacle 12, which motor being identical with that fully described in the aforesaid Letters Patent to Augustine Davis need not 80 be herein more particularly set forth.

It is the purpose or object of the present invention, as is the case in the patent to Augustine Davis hereinabove referred to, to provide 85 a machine which shall be effectively water-sealed against the escape of gas on both sides of the water inlet and discharge and without the use of valves; but it is an additional object of the present invention to provide simpler, more conveniently located, and generally more 90 efficient means for this purpose than in the patent mentioned. To this end for the charging of the generation-chamber with water we tap the side wall of the latter by an inlet-pipe 17, the upper end of which enters through the 95 lower end of a small tank 18, attached to the side wall of the generation-chamber, and is surmounted by a hood 19, the top of the tank

18 being closed by a removable lid 20. When water is poured into the upper end of the tank 18 in flushing the machine, the water rises around the upper end of the pipe 17 between it and the inner surface of the hood 19 until it overflows the upper end of the pipe and descends therethrough into the generation-chamber, and when the supply of water to the tank 18 ceases there is left a body of water in the lower portion of the tank 18, as seen in Fig. 1, which forms a liquid seal against the backward escape of gas and odors accompanying the same. On the opposite side of the main tank or shell of the machine and wholly externally of the lower end portion thereof is located a closed drainage-chamber 21, to the outer surface of which latter is applied an overflow-chamber 22, which communicates with said drainage-chamber through a port or opening 23 near the lower end of the outer wall of said drainage-chamber, whereby bodies of liquid in said chambers may freely communicate and be maintained at the same level. The overflow-chamber 22 has an overflow-spout 24 near its upper end, which determines the maximum height of the liquid in the two chambers under normal conditions.

The overflow for the water from the generation-chamber into the drainage-chamber is provided for as follows: 25 designates a horizontal pipe tapped in through the outer shell 5 at a point above the drainage-chamber, said pipe lying directly under the lower edge of the bell and at its inner end tapping the lower end of the inner cylinder 11, constituting the wall of the carbid-discharge chamber. The outer end of the pipe 25 is connected by a suitable T-coupling 26, plugged at its outer end with a pipe 27, which descends through the cover of the drainage-chamber 21 nearly to the lower end of the latter, whereby the overflow-pipe constituted by the pipe-sections 25 and 27 and the coupling 26 is constantly sealed.

The object of plugging the outer end of the pipe 25 or of the T-coupling which unites said pipe to the pipe 27 is to enable the pipe 25 to be readily cleaned from the outside of sediment which accumulates therein by the withdrawal of the plug and the insertion of a rod or scraper.

28 designates a pipe connected to and communicating with the overflow-pipe 25 through a suitable T-coupling 29, the upper end of which pipe is surrounded by a hood 30, fastened to the top of the pipe, the lower end of which hood terminates below the level of the sealing liquid in the bell, being provided with a series of minute perforations through which the gas passes, bubbling up through the surrounding liquid, whereby it is washed, and passing thence through another surrounding hood 31 to the interior of the gas-holder bell, all as fully set forth and described in the patent to Augustine Davis hereinabove referred to.

65 Behind these parts, as they are shown in Fig.

1, is located a filter, (indicated at 32, Fig. 2,) the top of which is in free communication with the interior of the upper end of the bell by a pipe 33, while its lower end is tapped by a service-pipe 34, this latter having a service-pipe drain in the form of a vertical pipe 35 tapping said service-pipe and descending through the cover or top wall of the drainage-chamber into the body of the liquid contained therein.

36 designates a safety blow-off pipe located inside the bell, its lower end extending out through the wall of the main shell or tank 5, also above the drainage-chamber, and provided with a short vertical pipe 37, communicating with its outwardly-extending horizontal member, and at its lower end tapping the cover of the drainage-chamber, stopping short of the upper surface of the liquid therein.

38 is a tube secured to and through the roof of the bell and surrounding the safety blow-off pipe 36, said tube 38 having a series of openings 39 so located as to effect the normal sealing of the safety blow-off tube 36, but to permit the venting of the gas through the latter when the bell rises to an abnormal or dangerous height in the manner fully disclosed in the patent to Davis before referred to.

In connection with the recharging of the generation-chamber with water it is of course essential to provide some means for venting the air contained therein in order to get rid of the same and prevent its subsequent mixture with and deterioration of the gas subsequently generated. A simple means for effecting this result is shown herein in the form of a short bent pipe 40, the horizontal member of which taps the overflow-pipe 25 through the coupling member 26, while the vertical member descends through the cover of the drainage-chamber into the upper end of the latter above the sealing liquid, this pipe being provided with a stop-cock or valve 41, which may be operated by hand or may be connected with the cover 20 of the water-inlet tank 18 by any suitable mechanism, so as to be opened and closed simultaneously with the latter in the manner disclosed in the patent to Davis hereinbefore referred to.

The operation, briefly described, is as follows: The valve 41 and the cover 20 having been opened water is poured into the tank 18 and rising inside of the hood 19 flows into and down the inlet-pipe 17 into the generation-chamber, the water as it enters the latter displacing the air and driving the same out through the pipes 25 and 40 into the upper portion of the drainage-chamber, whence it is vented to the atmosphere through the blow-off pipes 37 and 36. As soon as the water in the generation-chamber rises to the level of the lower portion of the horizontal overflow-pipe 25 it flows through the latter and descending through the pipe 27 fills the drain-

age and overflow chambers 21 and 22 to the level of the overflow 24. Upon the operation of the carbid-feed mechanism the carbid falls into the water, thereby generating the gas, which rises through the pipes 25 and 28, thence through the washing apparatus surmounting the upper end of the pipe 28 and into the upper sealed end of the bell, whence it passes down through the pipe 33 into and through the filter 32, passing thence into and through the service-pipe 34 to the burners.

This machine is of the type wherein the generation-chamber is designed to be periodically flushed with a fresh supply of water in the manner illustrated in the patent to Davis above referred to, although we have not herein shown means for effecting such periodical flushing. It will be obvious, however, that the mechanism shown and described permits such flushing to occur while maintaining a uniform height of liquid in the generation-chamber at a point which completely fills the latter and obviates the existence of an air-space within the latter above the surface of the water, and, further, that the water may thus pass entirely through the machine without breaking the water seal at either end and without requiring the use of valves. The chief advantage of our invention, however, resides in the fact that the location of the drainage-chamber 21 outside of the main casing of the machine permits it to be readily gotten at for the purpose of cleaning or mending the pipes communicating therewith without the necessity of dismantling the main body of the machine.

We claim—

1. In an acetylene-generator, the combination with a generation-chamber, of a drainage-chamber located wholly externally thereof, and a valveless water-sealed overflow connection between said generation and drainage chambers, said connection comprising a substantially horizontal pipe tapping said generation-chamber and leading outwardly to a point above said drainage-chamber and containing a removable plug in its outer end, and a depending pipe from said outer end of the horizontal pipe extending into the drainage-chamber and terminating below the water-level therein, substantially as and for the purpose described.

2. In an acetylene-generator, the combination with the generation-chamber, of a drainage-chamber closed at its upper end located wholly externally thereof, an overflow-chamber in free communication with the lower portion of said drainage-chamber, and an overflow-pipe communicating with the upper end of the generation-chamber and extending through the cover of the drainage-chamber below the level of the liquid therein, substantially as described.

3. In an acetylene-generator, the combination with the generation-chamber and a super-

posed water-sealed bell, of a drainage-chamber located wholly externally of said generation-chamber, an overflow-pipe communicating with the upper end of the generation-chamber and extending into said drainage-chamber, and a pipe tapping said overflow-pipe and serving to conduct the gas from said generation-chamber into the upper sealed portion of the bell, substantially as described.

4. In an acetylene-generator, the combination with an outer shell or casing having a generation-chamber in its lower end and a superposed water-sealed bell telescoping its upper end, of a drainage-chamber located wholly externally of said outer shell, a gas-conducting pipe connecting the space above said generation-chamber with the sealed upper portion of the bell, and a gas-discharge conduit connecting the latter with a service-pipe, and a water-sealed service-pipe drain-tube entering said drainage-chamber, substantially as described.

5. In an acetylene-generator, the combination with an outer shell or casing having a generation-chamber in the lower end thereof and a superposed water-sealed bell in its upper portion, of a water-sealed water-inlet pipe communicating with said generation-chamber, a drainage-chamber located wholly externally of said outer shell, an overflow-pipe connecting the upper end of said generation-chamber with said drainage-chamber and terminating in a water-sealed pipe in the latter, and a valved vent-pipe also in communication with the upper portion of said generation-chamber and serving to vent the latter of air when refilled with water, substantially as described.

6. In an acetylene-generator, the combination with an outer shell or casing having a generation-chamber in its lower end and a superposed water-sealed bell in its upper end, of a drainage-chamber closed at its upper end located wholly externally of said outer shell, an overflow-chamber in free communication with the lower portion of said drainage-chamber, an overflow-pipe connecting said generation and drainage chambers, a blow-off pipe leading from the gas-space of the bell out through the outer shell above said drainage-chamber and having a branch pipe entering said drainage-chamber above the level of the liquid therein, a valved vent-pipe establishing communication between the space above the generation-chamber and the water-sealed upper end of the drainage-chamber, and a service-pipe having a drain-tube attachment also entering said drainage-chamber and extending below the level of the liquid therein, substantially as described.

AUGUSTINE DAVIS.
